UNITED STATES PATENT OFFICE

171,294

BOTTLE

Julius Braun, Chicago, Ill.

Application July 13, 1953, Serial No. 25,892

Term of patent 14 years

(Cl. D58—9)

To all whom it may concern:

Be it known that I, Julius Braun, a citizen of the United States and a resident of Chicago, Illinois, have invented a new, original, and ornamental Design for a Bottle, of which the following is a specification, reference being had to the accompanying drawing forming a part thereof.

The sides of the bottle not shown are the same as those shown.

I claim:

The ornamental design for a bottle, substantially as shown and described.

JULIUS BRAUN.
